United States Patent Office.

WILLIAM W. WINTER AND THEODORE MUELLER, OF PHILADELPHIA, PENNSYLVANIA.

Letters Patent No. 76,129, dated March 31, 1868.

IMPROVEMENT IN UMBRELLAS.

The Schedule referred to in these Letters Patent and making part of the same.

TO ALL WHOM IT MAY CONCERN:

Be it known that we, WILLIAM W. WINTER and THEODORE MUELLER, of Philadelphia, Pennsylvania, have invented an Improvement in Umbrellas, &c.; and we do hereby declare that the following is a full, clear, and exact description of the same, reference being had to the accompanying drawing, and to the letters of reference marked thereon.

Our invention consists in fixing a cup or drip-reservoir to the end of an umbrella-stick, outside of or beyond the covering. As shown in the accompanying sheet of drawings, it is similar in construction to an ordinary umbrella, capable of opening and closing. On reference to the accompanying drawing, making a part of this specification—

Figure 1 is a sectional view, showing the cup or drip-reservoir closed, its relative position while umbrella is closed.

Figure 2 shows the umbrella closed, and the cup open to receive the rain from it; and

Figure 3 shows the method of securing the ribs of the cup or drip-reservoir to the crown of the same, whereby it is made self-opening.

Similar letters refer to similar parts in the several views.

A is an umbrella of the pattern common in use, to the stick, B, of which, at its upper end, and outside of the covering, is attached an adjustable or opening and closing drip-cup or rain-reservoir, C. It is constructed, in this instance, like an ordinary umbrella, having ribs, over which the material forming the cover is stretched, with the exception that the ribs are the loose ends of a series of wire springs, a, which are coiled around the wire strip or ring b, which forms the crown of the reservoir or cup C, so that when the ring c, which is slipped over the cup to keep it closed when not in use is removed, the ribs or loose ends, d, of the springs a, react and distend it, and upon the umbrella being placed in an inverted position, or, in other words, the cup-end downwards, the rain from it drips into and is held in the cup C until removed.

What we claim as our invention, and desire to secure by Letters Patent, is—

The expanding drip-cup C, the ribs of which form the loose ends d of a series of springs a, in combination with the closing-ring c, substantially as shown.

In testimony whereof, we hereunto sign our names to this specification in presence of two subscribing witnesses.

WILLIAM W. WINTER,
THEODORE MUELLER.
